UNITED STATES PATENT OFFICE.

JOHN S. FREESE, OF BROOKLYN, NEW YORK.

BUTTON-HOLE SEWING-MACHINE.

SPECIFICATION forming part of Letters Patent No. 244,578, dated July 19, 1881.

Application filed May 4, 1881. (No model.)

To all whom it may concern:

Be it known that I, JOHN S. FREESE, a citizen of the United States, residing at Brooklyn, in the county of Kings and State of New York, have invented new and useful Improvements in Button-Hole Sewing-Machines, of which the following is a specification.

This invention relates to certain improvements in the feed mechanism of a button-hole sewing-machine, such as described in Letters Patent of the United States, Nos. 183,333, 197,528, and 219,656.

This mechanism comprises a horizontally-rotating feed-wheel constructed with a circular groove and a cam-groove, a feed-dog and a brake-dog, both engaging the circular groove and serving to adjust automatically the stroke of the feed-dog. In my present improvement the tail of the feed-dog extends over the head of the brake-dog, and the feed-dog is acted on by a slide-bar which is guided in an adjustable cap, and directly acted on by a fixed and an automatically-adjustable cam in the end of the feed-lever, as will be hereinafter more fully explained.

This invention is illustrated in the accompanying drawings, in which Figure 1 represents an inverted plan. Fig. 2 is a top view of the feed-lever.

Similar letters indicate corresponding parts.

In the drawings, the letter A designates the bed-plate of the machine; B, the feed-wheel; C, the feed-dog, and D the brake-dog. Both these dogs catch in a circular groove, a, which is formed in the feed-wheel B side by side with a cam-groove, b, the feed-wheel being placed into a cavity in the top of the bed-plate, and the grooves a and b being made in the feed-wheel to allow the dogs to engage the circular groove a. The tail c of the feed-dog C extends over the brake-dog D, while the tail d of the brake-dog extends into a cavity, f, in the under surface of the bed-plate. From the bottom of this cavity rise two pins, g h, and to the pin h are hitched two springs, i j, one above the other, the spring i being attached to the feed-dog and the spring j to the brake-dog. I have shown the spring i broken off in order to more clearly illustrate the connection of the spring j with the brake-dog, but, of course, in practice the spring i has one end attached to

the stud h, as before stated. The end of the tail of the brake-dog is beveled, and it bears against the pin g, being held up against said pin by the spring j. The brake-dog therefore permits the feed-wheel to turn in the direction of the arrow marked on it in Fig. 1, but it prevents the same from turning in the reverse direction. By placing the brake-dog beneath the feed-dog I gain several advantages: First, I require a comparatively small opening in the bed-plate to permit both dogs to engage the circular groove a in the feed-wheel, and the strength of the bed-plate is not unnecessarily impaired; second, the tooth of the feed-dog can be made almost of any desired length, so that the danger of breaking the rim of the feed-wheel is avoided.

The tail of the feed-dog is pressed up by its spring i against the end of a slide-bar, E, which is guided by a cap, F, and by a screw, G, which passes through a slot, k, in the slide-bar E and screws into the bed-plate A, the cap F is secured to the bed-plate A by screws l l, which pass through slots m m in the cap, so that by releasing said screws the cap can be moved up or down, and thereby the slide-bar is caused to bear upon the feed-dog at different points and the length of the stitches is modified.

The slide-bar E receives its motion by the feed-lever H. This feed-lever has its fulcrum on a screw-stud, n, secured in the bed-plate A, and it is provided on its rear end with a roller-stud, o, which engages with a cam-groove, p, formed in a disk, I, which is mounted on a vertical shaft, J. The front end of said feed-lever forms a box, q, which contains two cams, r s, the cam r being retained in said box by a screw, t', on which it oscillates, and being adjusted in the required position by a setscrew, t, while the cam s slides in the box and is exposed to the action of a bell-crank lever, K, which has its fulcrum on a screw, u, secured in the upper surface of the feed-lever, (see Fig. 2,) and the long arm of which has a curved edge, which bears against a projection, v, on the inner edge of the cams. The short arm of the bell-crank lever K connects by a rod, w, with an elbow-lever, L, that has its fulcrum on a screw, a', secured in the bed-plate A, and on said elbow-lever is secured a roller-stud, b', which engages with the cam-

groove *b* of the feed-wheel and moves in a slot, *c'*, in the bed-plate, Fig. 1. The rod *w* passes through a hole in the end of the elbow-lever *L*, and is provided with a nut, *d'*, and 5 jam-nut *e'*. A spring, *f'*, acts on the bell-crank lever *K*, and has a tendency to throw this lever in such a position that the movable cam *s* is forced outward. By adjusting the nuts *d'* *e'* the bell-crank lever *K* is retained 10 against the action of its spring, so that the movable cam *s* is not allowed to move outward beyond the desired point. As long as the roller-stud *b'* of the elbow-lever *L* is situated in the inner portion of the cam-groove *b* of the 15 feed-wheel, the movable cam *s* is thrown forward to the position shown in Fig. 1, and as the feed-lever *H* oscillates the said cam *s* acts upon the slide-bar *E*, and for each stroke of the feed-lever a uniform motion is imparted to 20 the feed-dog and to the feed-wheel, so that stitches of uniform length are produced; but when the outer portion of the cam-groove *b* in the feed-wheel comes to act upon the roller-stud *b'* of the elbow-lever this elbow-lever 25 swings in the direction of the arrow marked on it in Fig. 1, the bell-crank lever *K* is forced down against its spring *f'* a certain distance, and the movable cam *s* falls back, so that the cam *r* acts upon the slide-bar *E* and the length 30 of the stitches is increased.

It will be seen from this description that the slide *E* bears at one end against the tail of the feed-dog and at its opposite end against the cams *r* *s* in the feed-lever, so that no connection is required at either end, and that by ad- 35

justing the cap *F* the length of the stitches can be varied. The long stitches can be separately adjusted by the set-screw *t* and cam *r*.

What I claim as new, and desire to secure by Letters Patent, is—

40

1. The combination, substantially as herein-before described, of the bed-plate *A*, feed-wheel *B*, situated in a cavity in the upper surface of the bed-plate, the feed-dog *C*, and the brake-dog *D*, the latter being situated beneath the 45 feed-dog.

2. The combination, substantially as herein-before described, of the feed-dog *C*, the feed-lever *H*, and the slide-bar *E*, bearing at one end against the tail of the feed-dog, and at its op- 50 posite end against the end of the feed-lever.

3. The combination, substantially as herein-before described, of the feed-dog *C*, the feed-lever *H*, the slide-bar *E*, bearing at one end against the tail of the feed dog, and at its op- 55 posite end against the end of the feed-lever, and the cap *F*, which guides the slide-bar and is adjustable for varying the length of the stitches.

4. The combination, substantially as herein-before described, of the feed-lever *H*, the sliding cam *s*, the adjustable cam *r*, the bar *E*, and the feed dog *C*, and the feed-wheel *B*. 60

In testimony whereof I have hereunto set my hand and seal in the presence of two subscr- 65

ing witnesses.

JOHN S. FREESE. [L. s.]
